UNITED STATES PATENT OFFICE.

JOHN B. PRICE, OF TUTTLE, KENTUCKY.

WATER RAISING AND EMPTYING DEVICE FOR WELLS.

SPECIFICATION forming part of Letters Patent No. 613,017, dated October 25, 1898.

Application filed January 22, 1898. Serial No. 667,589. (No model.)

To all whom it may concern:

Be it known that I, JOHN B. PRICE, a citizen of the United States, residing at Tuttle, in the county of Knox and State of Kentucky, have invented certain new and useful Improvements in Water Raising and Emptying Devices for Dug, Driven, or Drilled Wells; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in devices for drawing and emptying water from open wells of that class that are operated by means of a windlass; and the objects of my invention are, first, to provide a device of the class described wherein the well-bucket is lowered, raised, and emptied simply by turning the windlass; second, that has a means for automatically opening and closing the well-cover; third, that has an automatic means for tripping the shifting-lever, so it will be in readiness for allowing the bucket to be lowered, and, fourth, to provide a device of that class that will be simple in construction, easy of operation, and convenient withal.

With these objects in view my invention consists in the construction and combination of parts shown in the accompanying drawings and described in the following specification.

In the drawings Figure 1 is a perspective view of the device complete, with the well-curb. Fig. 2 is a side elevation. Fig. 3 is a front elevation. Fig. 4 is a top plan view taken on the line X X of Fig. 3, and Fig. 5 is a detail view of the bucket-shifting lever.

Referring to the drawings, 1 is the well-curb, having the water-bucket shelf 2 in front and uprights 3 and 4 at either side. The curb is inclosed on all sides and top and has a circular opening in the top to admit the well-bucket, said opening being provided with a lid 5. The uprights 3 and 4 are connected at the top by a piece 6, which carries a pulley 7 directly above the center of the lid 5. Rotatably mounted in the upright 3 is a windlass 8. A cross-piece 9 extends from upright to upright

near the top and has pivotally hung thereto the shifting-lever 10 and the trip-dog 11. The shifting-lever 10 has secured to its lower end 55 an arm 12, terminating in an elongated loop 13, and on the rear side, near the lower end, is a pin 14, which engages with the trip-dog 11.

Upon the top of the curb 1 is a trough 15, pivotally mounted between short posts 16, 60 the rear end of the trough being weighted, so as to cause it to normally rest upon the block 17, as seen in the dotted lines in Fig. 2. Secured to the end of the hinge-rod 18 of the lid 5 is a segmental slotted arm 19. A pin 20 in 65 the adjacent side of the trough 15 extends into the slot of the arm 19. Hence when the trough moves up or down the lid 5 is raised or lowered, as the case may be. The position of the segmental slotted arm 19 with relation to the pin 20 causes the lid 5 to open to a perpendicular position with a very small movement on the part of the trough 15, which is illustrated by the dotted lines in Fig. 2.

A rope or cable 21 is secured to the windlass 8, passes over the pulley 7, and is secured to the bail of the well-bucket 22. Just above the bail of the bucket the rope is provided with a button or ball 23, securely fastened thereto. A rod 24 passes from upright 3 to 80 4 for the purpose of preventing the bucket 22 from slipping down in the trough 15 when at rest. Secured to the end of the trip-dog 11 is a rod 25, passing down the inside of upright 4 and having an inwardly-extending 85 end, which engages with the striker 26, secured to the side of the trough. The well-bucket 22 is of the type which have a bottom valve, which permits the bucket to fill itself from the bottom and also to empty itself 90 when set down by reason of the valve being forced open; but while being raised from the well the weight of the water holds the valve closed and prevents the escape of the water.

In operation the apparatus is first in the 95 position shown in Fig. 1. The windlass is turned, lifting the bucket, which swings over the lid 5, and when the weight of the bucket is taken from the trough in front of its pivotal point it drops back by reason of the 100 heavy rear end and thereby raises the lid 5 through the medium of the segmental slotted arm 19 and the pin 20. The bucket is then let down in the well, where it fills, and is drawn

up until it reaches the position indicated by the dotted lines in Fig. 3, where the button 23 engages the loop 13 of the arm 12, secured to the pivoted shifting-lever 10, and as the bucket is further raised the button, catching in the loop, causes the lever 10 to shift the position of the bucket until it hangs directly over the trough, as seen in Fig. 3. To gain this position, the arm 12 has assumed a horizontal position and brings the pin 14 on the lever 10 in contact with the notch in the trip-dog 11, which it engages and holds in place while the bucket is let down into the trough 15. When the weight of the bucket strikes the trough, it at once tilts forward, closing the lid 5 and causing the striker 26 to engage the rod 25 and disengage the trip-dog 11 from the pin 14 on the shifting-lever 10, and at the same time the valve in the bottom of the bucket is opened by coming in contact with the trough, releasing the water and permitting it to run down into the water-bucket placed upon the shelf 2 on the curb 1.

The extreme simplicity of the device is readily apparent, and the ease with which it may be operated will appeal to all those having a knowledge of the difficulty and labor connected with drawing water from deep-dug wells by means of any ordinary windlass.

It will be understood that the shape of the bucket 22 can be varied to accommodate it to wells of different diameters, the bucket shown being of the type used in dug wells, while for driven wells a long slender bucket is employed.

Having thus described my invention, what I claim, and desire to secure by Letters Patent of the United States, is—

1. A device for drawing and emptying water from dug, driven or drilled wells, consisting of an inclosed curb 1, having an opening in the top, provided with a hinged lid, and a bucket-shelf 2, secured to the front thereof; uprights 3 and 4, secured to either side of the curb and connected at the top by a piece 6, carrying a pulley 7; a windlass 8, mounted in the upright 3; a shifting-lever 10, and trip-dog 11, pivotally mounted upon a cross-piece 9, secured near the top of said uprights 3 and 4, said shifting-lever having an arm 12, terminating in an elongated loop 13, and having a pin 14 upon its rear side to engage the trip-dog 11; a trough 15, pivotally hung between posts 16, on the curb 1, said trough 15 weighted at its rear end and having a striker 26, upon one side and a pin 20 upon the other; a rod 25, passing along the upright 4, and secured at its upper end to the trip-dog 11, and having an inwardly-extending lower end to engage the striker 26; a bucket-supporting rod 24, secured to the uprights 3 and 4; a lid 5, having a hinge-rod 18, provided with a fixed segmental slotted arm 19, at one end; said slot engaging the pin 20, on the trough 15, and a rope or cable 21, secured to the windlass 8, passing over the pulley 7, through the loop 13, and secured to the bail of the bucket 22, said rope having a button 23, fixed thereon, just above the bucket-bail, all arranged substantially as set forth.

windlass 8, passing over the pulley 7, through the loop 13, and secured to the bail of the bucket 22, said rope having a button 23, fixed thereon, just above the bucket-bail, all substantially as shown and described.

2. In a device for raising water from dug, driven, or drilled wells and emptying the same automatically, the combination of the curb 1, having an opening at the top, provided with a lid, and a bucket-shelf 2, secured to the front thereof; uprights 3 and 4, secured to either side of the curb and connected at the top by a piece 6, carrying a pulley 7; a windlass 8, mounted in the upright 3; a shifting-lever 10, and trip-dog 11, pivotally mounted upon a cross-piece 9, secured near the top of said uprights 3 and 4, said shifting-lever having an arm 12, terminating in an elongated loop 13, and having a pin 14 upon its rear side to engage the trip-dog 11; a trough 15, pivotally hung between posts 16, on the curb 1, said trough weighted at its rear end and having a striker 26, upon one side and a pin 20, upon the other; a rod 25, passing along the upright 4, and secured at its upper end to the trip-dog 11, and having an inwardly-extending lower end to engage the striker 26; a bucket-supporting rod 24, secured to the uprights 3 and 4; a lid 5, having a hinge-rod 18, provided with a fixed segmental slotted arm 19, at one end; said slot engaging the pin 20, on the trough 15, and a rope or cable 21, secured to the windlass 8, passing over the pulley 7, through the loop 13, and secured to the bail of the bucket 22, said rope having a button 23, fixed thereon, just above the bucket-bail, all arranged substantially as set forth.

3. The combination in a device for raising and emptying water from dug, driven or drilled wells, of the water-raising devices, consisting of the curb and windlass, with the emptying devices, consisting of the shifting-lever, having the arm 12, terminating in an elongated loop 13, and having a pin 14, upon its rear side, the trip-dog 11, the rod 25, the tilting trough 15, button 23, on the rope 21, and the bucket 22, having a valve in the bottom thereof, as set forth.

4. In a water elevating and emptying device of the class described, the combination with the curb 1, the windlass 8, and the trough 15, of the lid opening and closing device, consisting of the segmental slotted arm 19, fixed upon one end of the hinge-rod 18, of the lid 5, said slotted arm engaging with a pin 20, upon the adjacent side of the trough 15, as shown and described.

In testimony whereof I affix my signature in presence of two witnesses.

JOHN B. PRICE.
